UNITED STATES PATENT OFFICE.

WILLIAM KAHLE, OF CHICAGO, ILLINOIS.

CARBURETING APPARATUS.

SPECIFICATION forming part of Letters Patent No. 743,085, dated November 3, 1903.

Application filed February 9, 1903. Serial No. 142,639. (No model.)

To all whom it may concern:

Be it known that I, WILLIAM KAHLE, a citizen of the United States, and a resident of the city of Chicago, in the county of Cook and State of Illinois, have invented certain new and useful Improvements in Carbureting Apparatus; and I do hereby declare that the following is a full, clear, and exact description of the same, reference being had to the accompanying drawings, and to the letters of reference marked thereon, which form a part of this specification.

This invention relates more particularly to an apparatus for generating a hydrocarbon illuminant gas, such as a mixture of vaporized gasolene or the like with atmospheric air.

The object of the invention is to provide a construction capable of rapidly vaporizing a hydrocarbon liquid, such as gasolene, and mixing therewith atmospheric air in proportion suitable for illuminating purposes.

It is also an object of the invention to provide as compact and simple a construction as possible so devised as to effectually prevent the escape of the hydrocarbon vapor or mixture therefrom except through the delivery-pipe and adapted to be constructed of any preferred size capable of installation wherever a mixing and generating device of the class described may be required.

The invention consists in the matters hereinafter described, and more fully pointed out and defined in the appended claims.

In the drawings, Figure 1 is a front elevation, partly broken away, of a device embodying my invention. Fig. 2 is a vertical section thereof parallel with the plane of the front and showing the fluid-elevator in elevation. Fig. 3 is a section taken on line 3 3 of Fig. 2. Fig. 4 is a section taken on line 4 4 of Fig. 3. Fig. 5 is an enlarged transverse section of the vaporizing and mixing drum. Fig. 6 is a fragmentary longitudinal section of the same. Fig. 7 is an elevation of the ends of the same, partly broken, and the fluid-elevator. Fig. 8 is a detail of one of the buckets on the chain elevator, illustrating its operation.

As shown in said drawings, the apparatus is contained within a cabinet A, adapted to protect the same from interference and to afford support for the operating parts thereof, and comprises a closed hydrocarbon-sup-

ply tank B, a gasometer C, having a carbureter D therein. The supply-tank B communicates with the gasometer through a pipe 55 b. A blowing and regulating device E is provided, and a motor F of any desired or convenient nature—as shown a weight-motor—operates the mechanism. As shown, said gasometer C comprises an upwardly-opening 60 tank or receptacle of sheet metal c, having a semicylindric lower end and having the upper edge flanged outwardly, as indicated at c' in Figs. 2 and 3. Secured on the outer side of said tank C is an outer casing c², having the 65 upper margin thereof flanged inwardly, and which provides between the same and the tank C a space to contain water, thereby forming a water-jacket. Supported on said tank C, with its margins extending downwardly between the walls of the tank and the casing c² into the water therein, is the inverted bell C'. The top of said cabinet acts to limit the upward movement of the bell when filled with gas, thereby compressing 75 the gas or mixture therein before the lower margins of the wall thereof can be elevated above the surface of the water in the water-jacket. For convenience, if preferred, rollers 80 c⁴ may be provided in said water-jacket, supported upon either the walls of the tank or casing, and which act to steady and direct said bell as it rises or falls with the varying gas-pressure within the gasometer.

Within the cabinet and forming a support 85 for the gasometer is the cylindric casing e of the blower E. Said casing contains within the same rotatable fan e' and is provided with a drain-pipe e², a valved supply-pipe e⁴, a gage-orifice e⁶, adapted to have secured there- 90 in a gage, and is kept somewhat more than half filled with water, as indicated in Fig. 2.

Journalized in the bottom of the gasometer-tank B and revolute therein is the vaporizing and mixing or carbureting device, (indicated as a whole by D.) Said carbureter, as shown, consists of a sheet of metal d, corrugated transversely and rolled to a spiral form, as shown in Figs. 2, 5, and 7, forming, as shown, a cylindric shell corrugated longitudinally and having a spirally-rolled interior portion, the inner end of said spiral terminating at the central shaft d² and is secured thereto. Said carbureter is provided

at the ends with flanges d^8 , projecting beyond the edges of the sheet forming the spiral, as shown in Fig. 6. As shown, the periphery of the carbureter is provided with a plurality of apertures elongated longitudinally of the same between the corrugations, and on one side of each is provided a downwardly-turned lip d' against the current of air admitted from the blower by the pipe E' , which communicates through the shell or casing of the blower and also through the bottom portion of the gasometer-tank C and is directed inwardly against the shell of the carbureter, as shown in Figs. 1 and 2.

15 Means of any desired kind may be used to drive the blower and rotate the carbureter. As shown, however, a weight F, adapted to be wound up in a familiar manner, acts to drive a sprocket-wheel f , the sprocket-chain 20 f' of which leads to a similar sprocket-wheel on the end of the shaft of the carbureter where the same projects through the gasometer-tank, thereby rotating the carbureter. The blower is rotated from the shaft of the 25 carbureter by means of suitable sprocket-wheels and sprocket-chains, as shown in Fig. 1, so that by the gravity of said weight the carbureter and blower are simultaneously operated. The liquid in the blower-chamber 30 by its resistance to the fan acts to regulate the descent of the weight and the rotation of the carbureter.

The gasolene or other hydrocarbon tank B may be of any desired form or size and, as 35 shown, is located within the cabinet and provided with a delivery-pipe b , which communicates through the shell of the gasometer-tank near its bottom to a point below the carbureter, thereby permitting the fluid hydrocarbon to flow into the gasometer-tank ordinarily through a passage, which may of course be valved, or providing other means for regulating the delivery therethrough, as preferred. Said gasolene or other hydrocarbon 45 fuel is elevated from the bottom of the gasometer-tank and delivered into the central portion of the carbureter by means of the chain elevator D' , which, as shown, is provided with buckets d^4 , which are closed 50 on all sides except along a comparatively narrow aperture near the outer edge of the bucket, as shown in Fig. 8. As the said elevator-chain is driven by the rotation of the carbureter each of the buckets scoops up a 55 portion of the hydrocarbon fluid and carries the same to a point above the carbureter-shaft and pours the same into the trough D^2 , as shown in Fig. 6, which delivers the same into the carbureter at a point near the center.

60 A delivery-pipe b' is provided leading from the gasometer outwardly to the system of distribution, and, as shown, the inner end of said pipe is provided with an upwardly-turned elbow extending sufficiently high within the 65 gasometer to prevent any of the liquid hydrocarbon finding its way therein. A filling-pipe b^2 communicates with the closed supply-

reservoir. Obviously any variety of indicating devices—such as gages, glasses, cocks, or the like—may be used to indicate the level of the fluids in the various portions of the device.

The operation is as follows: The device, constructed as described and having a sufficient amount of water in the water-jacket 70 surrounding the gasometer to prevent escape of gas therefrom and having the blower-chamber partly filled with water, as indicated in Fig. 2, is started in operation by winding up the weight F, whereupon gravity of the 75 weight causes the rotation and operation of the blower and carbureter, forcing atmospheric air into the gasometer-chamber against the apertured side of the carbureter as the same revolves. The liquid hydrocarbon flowing into the bottom of the gasometer-tank from the tank B is scooped up by the buckets of the chain elevator and carried over the shaft of the carbureter and poured into the spout D^2 , flowing therefrom into the carbureter, near the middle thereof. As the carbureter is revolved the air from the pipe E' passes inwardly through the shell of the carbureter, following the spirals, and becomes thoroughly mixed with the vapor of the hydrocarbon, which is violently agitated as it flows over the corrugations along the spirals. The mixed vapor or gas flows outwardly at the ends of the carbureter into the gasometer, producing gaseous pressure therein and 100 lifting the bell in a familiar manner, and as the upward movement of the bell is limited by the top of the cabinet the pressure therein augments, thereby resisting the inflow of hydrocarbon from the supply-tank. The 105 mixture of hydrocarbon gas and air may now be used in the usual manner for combustion, illuminating, or other purposes, the same flowing outwardly from the tank of the gasometer through the delivery-pipe. Obviously 110 the descent of the weight may be regulated very perfectly by the amount of fluid or liquid in the blower-chamber and the number of paddles and the obliquity of the paddles with respect to the surface of said liquid. Other regulating means, however, may be employed, if preferred, and any motor or 115 desired source of power may be utilized, as preferred. Obviously the flow of the hydrocarbon fluid into the gasometer-tank is automatically regulated by the means of the pressure within the gasometer, the flow being decreased as the pressure augments and of course increased as the pressure is exhausted.

The apparatus embodying my invention may be constructed of any desired size and the parts may be differently assembled with respect to each other and many details of construction may be varied without departing from the principles of this invention.

I claim as my invention—

1. The combination with a gasometer, of a source of liquid-hydrocarbon supply, a revolvable carbureter into which the hydrocarbon

is delivered centrally from the source of supply, means for creating a blast of air and a plurality of outwardly-directed lips on the carbureter adjacent apertures therein, and 5 adapted to direct the air-current into the carbureter.

2. The combination with a spirally-divided revoluble carbureter, of a source of liquid-hydrocarbon supply leading centrally thereinto, 10 means for creating a blast of air, outwardly-directed lips peripherally arranged on the carbureter adjacent to apertures therein and adapted to catch the air-blast and force it inwardly against said hydrocarbon and a gasometer into which the resulting mixture of 15 hydrocarbon vapor and air is delivered.

3. The combination with a gasometer, of a mixing and carbureting device therein comprising a spirally-wound corrugated sheet, a 20 source of fluid-hydrocarbon supply connected to deliver axially of the carbureter, an inwardly-directed flange on the edges of said sheet, a plurality of outwardly-extending lips on the carbureter, means for directing air 25 against said lips and into the carbureter and operating means therefor.

4. In a device of the class described the combination with a gasometer, of a carbureter therein comprising a spirally-wound corrugated metallic sheet, a source of hydrocarbon-supply leading into the center thereof, means adapted to rotate the carbureter and force the hydrocarbon outwardly thereof over 30 said corrugations, means for creating a blast 35 of air, outwardly-directed lips on the periphery of the carbureter adapted to direct the air inwardly against the hydrocarbon and means for operating said device.

5. In a device of the class described, a gasometer having a semicylindric bottom, a revoluble carbureting and mixing device in the bottom thereof, comprising a corrugated spirally-divided cylindric shell, outwardly-directed lips on its periphery, means for delivering 40 liquid hydrocarbon to the interior of the carbureter and mixer, means for delivering 45 air under pressure also thereinto, said

carbureter acting to agitate the contents thereof together, and to deliver the same as a mixed vapor into the gasometer.

6. A carbureter for the purpose specified comprising a cylindric shell of longitudinally-corrugated metal and having a spiral partition comprising a sheet of metal wound or rolled to provide a spiral interior, the exterior of said carbureter having a plurality of slotted apertures extending therethrough.

7. A carbureter for the purpose specified comprising a sheet of transversely-corrugated metal rolled to provide a cylindric shell and spiral interior, the inner end of the sheet being secured to a central shaft with which the carbureter rotates and relatively narrow flanges at each end of the carbureter along the edges of the sheet forming narrow end walls.

8. In a device of the class described the combination with a gasometer, of a spirally-divided revoluble carbureter therein, means for delivering liquid hydrocarbon thereinto comprising an endless chain, buckets thereon adapted to dip the liquid hydrocarbon from the bottom of the gasometer and a trough adapted to receive the hydrocarbon from the buckets and deliver it to the carbureter.

9. The combination with a gasometer, of a carbureter comprising a spirally-wound corrugated sheet, means for directing a blast of air thereinto, means for delivering liquid hydrocarbon to the center of the carbureter comprising an endless chain, a plurality of 70 outwardly-directed buckets thereon having a transverse opening in the outer end thereof adapted to dip liquid hydrocarbon from the bottom of the gasometer and a trough adapted to receive the hydrocarbon from said buckets 80 and deliver it to the carbureter.

In testimony whereof I have hereunto subscribed my name in the presence of two subscribing witnesses.

WILLIAM KAHLE.
